William A. Darrah, Inventor.

UNITED STATES PATENT OFFICE.

WILLIAM A. DARAH, OF CHICAGO, ILLINOIS.

PROCESS OF HEATING GASES AND EQUIPMENT THEREFOR.

Application filed April 25, 1923. Serial No. 634,642.

To all whom it may concern:

Be it known that I, WILLIAM A. DARAH, a citizen of the United States, residing at Chicago, in the county of Cook and State 5 of Illinois, have invented a new and useful Improvement in Processes of Heating Gases and Equipment Therefor, of which the following is the specification.

This invention relates to methods of heating air or other gases, and equipment for carrying out said heating process effectively and economically and at a reasonably small expense for equipment.

This invention more particularly applies 15 to the heating of air and other gases in large quantities for industrial operations, such as the drying of salt, sugar, starch, sand, and similar materials, although the air thus heated may also be employed for the heating 20 of buildings, and any other applications where a source of heated air or other gases are required.

This process and equipment is particularly related to the so-called class of indirect heaters, in which the products of combustion do not ordinarily intermingle with the air or gases to be heated. Provision is made, however, in this equipment, for allowing 30 said products of combustion to intermingle with the air or gases which are heated.

Any desired source of heat may be employed with this equipment but the best results are ordinarily secured using fuels such 35 as coal, oil, gas and related products. The invention, however, is not limited to the fuel used, as any fuel or other source of heat may be satisfactorily utilized.

In the description which is here given, 40 the specific illustration of a process and furnace for heating air is chosen for purposes of clearness in illustrating the invention. It should be understood, however, that where the word "air" is used throughout the specification or claims, any other gases may be substituted. For purposes of illustration also, the drawings show an oil heated furnace. It will be evident that other fuels may be used, making simple modifications 45 in the design. In the case of coal we prefer to use a stoker for maintaining a uniform heat. This is not essential, however,

although it is frequently of practical advantage.

Some of the objects of this invention are 55 to effectively and efficiently heat air or other gases with the minimum size of heating equipment and with the minimum loss of heat. Other objects will be evident from a perusal of the specification and claims. 60 Other objects will also be referred to in the course of the description given in this specification.

Upon referring to the drawings, Figure I shows a front elevation, in section, of one 65 form of device for carrying out my invention. Figure II shows a side elevation of a heater built in accordance with this invention, the section being shown through the combustion chamber. Figure III shows a 70 side elevation partly in section, the elevation being taken through the air passages. Figure IV shows a plan view in section.

In the drawings the arrows which are shown in dotted lines indicate the path of 75 the products of combustion, while the solid arrows indicate the path of the air or other gases which are being heated.

Referring to the drawing, (1) represents the furnace foundation carrying base wall 80 (2) which is interspersed at the necessary hot points with highly insulating material (3). Furnace walls (4) enclose the structure while strips of highly insulating material (5) are placed in such position as to 85 surround the warmer parts of the furnace. Combustion chambers (6) are provided within the walls (4), and in the specific case illustrated, three chambers are shown, numbered respectively 6, 7 and 8. The walls 90 (9) of combustion chambers (6, 7 and 8) are preferably made of a highly conducting and very refractory material, such as carborundum. They may be readily built up of carborundum brick cemented together, or they may be made of tile, or formed in a single piece.

The carborundum or highly conducting portion of combustion chamber (6) is preferably connected at one extremity with a 100 flue member (10) provided with baffle (11) and carrying on its upper surface metal conducting flues (12, 13 and 14). These flues are arranged to connect one into the other,

and eventually, by means of breeching (15), lead to stack (16). It is desirable to make the walls (9) of combustion chamber (6) out of highly conducting refractory material, but for economical reasons it is not desirable to make it of sufficient strength to carry the load of the flue members of the furnace. These metal flue members (12, 13 and 14) therefore rest upon a refractory flue member (10) which is of course subjected to less severe temperature conditions than the combustion chambers and which because of its thicker walls and lower grade material is less expensive. Since the material used in the combustion chamber (6) is different from the material used in the flue member (10) these two portions should preferably not be bonded together but should be closely adjacent so as to prevent leakage from the combustion chamber to the air spaces (17, 18, 19, 20 and 21). The bonding together of these two parts would of course result in unequal expansion, which would cause the structure to crack. Likewise, since the temperatures of the combustion chambers (6, 7, and 8) and flues (10, 10^A and 10^B) are much higher and fluctuate more widely than the temperature of the walls of the furnace, it is essential that the flues, combustion chambers etc., be constructed in such a way that they are free to expand without moving the wall member and that they are not bonded to the wall member in any way.

The combustion chamber walls, and other heat conducting walls of the furnace, are preferably formed with many rough projections which serve to cause eddies in the air and gases which move over them, thus maintaining the walls at substantially the temperature of the gases. By this device it is possible to materially increase the number of heat units which are convected over the walls to the air or gases to be heated, or conversely, to increase the number of heat units which are transmitted over the products of combustion or flame to the walls. The effect of irregularities of this kind are therefore to materially decrease the surfaces necessary for handling the heat. This reduction in necessary surface area naturally makes the equipment much less expensive, more compact and more effective. Typical projections on the chambers are indicated by reference numeral (22), and similar projections on the flues by numeral (23).

In order to secure the maximum travel for the gases which are to give up their heat, baffles (24 and 25) are placed in combustion chamber (6). Baffles (24 and 25) also serve to tie together the vertical walls (26 and 27) of combustion chamber (6). Without the tying effect of baffles (24 and 25) the relatively tall thin walls of the combustion chamber would frequently be too unstable for commercial purposes. It will of course

be apparent that by making walls (26 and 27) sufficiently thick the necessity for the stabilizing effect of baffle walls (24 and 25) could be eliminated, but this would again mean a materially thicker wall and one which would therefore not only be much more expensive but a poor conductor of heat. For these reasons the baffle walls (24 and 25) serve a very desirable structural purpose as well as distributing the trapped flame and causing the products of combustion to travel through a longer path.

Referring to Figure II, it will be evident that the flame enters through burner (28), fills combustion chamber (6) and travels as shown, around baffles (24 and 25) to the upper portion of flue (10) and then out through metal passageways (12, 13 and 14) to the stack. We have found it economical to make metal flue member (12) of heat resisting alloy, while the adjacent member, shown in this case by portions (13 and 14), may to advantage be made of cast iron. The stack reaching, stay, etc., may be made of steel plate, brick, or other desired material. I have found it an advantage in connection with metal flues (typified by 12, 13 and 14) to form the side walls into a corrugated or saw-tooth section such that the flue gases are compelled to continually change their angle of flow. The continual change of the angle of flow causes the gases to impinge alternately on the various sides of the flues, thus maintaining the flues at substantially the temperature of the gases. By this device it is possible to materially increase the number of heat units which can be radiated or absorbed by a given number of square feet of flue surface. This formation also results in strength, and gives a structure which will readily permit expansion without serious warping or distortion.

Referring to Figures I, II and III, it will be noted that the air (or other gases to be heated) enters at the top of the furnace, travels downward through the elevated portion (30) until it encounters baffle wall (31), which causes the air current to turn, passing along and underneath baffle wall (31) in the space between baffle walls (31 and 32). The air to be heated then passes along the bottom of the furnace between the combustion chambers (6, 7 and 8) and finally upward at the front end of the furnace and out through opening (33) which is connected with the dryer (34).

It will be noted, therefore, that the air travels in an opposite direction to the flue gases or products of combustion. As a result of this arrangement, it will be evident that the greatest average temperature difference is maintained between the air to be heated and the flue gases which supply the heat. This arrangement gives the greatest possible efficiency, and at the same time, since

the amount of heat transmitted varies directly as the temperature difference, it will give the most compact and therefore the most inexpensive construction.

5 In order to secure the most complete contact between the air to be heated and the hot surfaces, various baffles have been provided which serve to deflect the air onto the hot surfaces and at the same time to create 10 eddies. Thus, baffles (35 and 36) serve to direct the incoming air down between various flue members (14, 13 and 12). In the same way, baffles (37, 38 and 39) serve to cause the incoming air to break into eddies 15 and to be deflected against the hot sections. In a similar manner the metal plate deflectors (40, 41 and 42) deflect the incoming air against the hot flues and create eddies.

It will be evident that the air within the 20 walls of the furnace portion (30) will be materially hotter than the air outside. This will tend to create a draft which would ordinarily cause the air to travel upward in the same direction as the flue gases. Obviously 25 this would defeat the object of the device. It will of course be understood that in normal operation the air is drawn through the dryer by a fan, shown diagrammatically as (45). Even, however, when fan (45) is in 30 operation, the "back draft" caused by the tendency of the hot gases in member (30) to rise, would result in a loss of considerable heat.

This condition is partly overcome by the 35 shape of members (40, 41, 42) and related members, which make the passage of the air in the normal direction easier than in the reverse direction. This same tendency is further overcome by the use of the adjustable 40 members (46 and 47), which are designed to close the opening between the breeching (15) and the brick walls (30) to such a degree that the velocity of the incoming air (caused by the suction of the fan) is sufficient 45 to prevent the escape of any of the heated air within the walls (30).

Heat absorbing walls (48 and 49) are typical of the construction which is placed around the highly heated portions of the 50 combustion chamber in order to secure the most effective heat transfer. Said walls (48 and 49) are not necessarily highly conducting material, and in ordinary commercial furnaces may be made of second quality 55 fire brick. The walls should be strong, durable, and preferably have a relatively rough surface. The advantage of the walls is derived from the fact that only a definite amount of heat can be absorbed when a gas 60 passes over a given number of square feet of hot surface. In other words, the amount of heat absorbed when a gas passes over a heated surface is approximately a function of the first power of the temperature. On 65 the other hand, the amount of heat which

may be radiated from a highly conducting wall, normally varies, as the cube, or even higher powers of the temperature. It will be evident, therefore, that in dealing with high temperatures, the amount of heat which 70 is radiated will be much in excess of the amount of heat which can be absorbed by forcing air over the hot surfaces. In order, therefore, to properly heat a stream of air (or other gases) it is necessary to provide 75 a definite number of square feet of radiating surface for any given temperature. Inasmuch, however, as good conducting refractories are relatively expensive, and further inasmuch as an air heating device becomes 80 large and bulky (and therefore expensive) if direct contact with the conducting refractories is depended upon, it is desirable to provide other means for accomplishing this result. The other means which I have devised are exemplified by walls (48 and 49) which receive by radiation a large amount 85 of heat which maintains them at a high temperature. The air passing over these walls, therefore, is heated, and the effect is 90 substantially the same as if the area of the highly conducting refractory walls were doubled. It will be noted also that walls (51 and 52) serve in the same manner as walls (49 and 48). At the same time, walls (51 95 and 52) act as enclosing walls for the furnace.

Doors (53 and 54) are provided to permit ready access to the interior of the combustion chamber for cleaning, inspection or 100 repairs.

Walls (48 and 49) also serve the further purpose of reducing the volume of the air space between adjacent combustion chambers (6, 7 and 8), thus bringing the air 105 velocity to the desired figure. The advantage in controlling the air velocity arises from the fact that too slow an air velocity causes the air to absorb too little heat as it travels through the furnace, thus entailing a large and expensive furnace. On the other hand, too high an air velocity through the furnace results in shortening the time the air is in the furnace and increasing the work necessary on the fan which draws the 110 air through the furnace.

In operating this device I have frequently found it of advantage to return the air which leaves the blower (45) to the intake of the furnace, or I may only return a portion of this air. I have also provided doors or outlets (55 and 56) which may be opened, thus permitting a portion of the flue gases to enter the heated air.

A furnace of the type here described will 125 readily give efficiencies under operating conditions ranging from 70 to 90%. An average efficiency exceeding 80% is the rule, and 85% may be secured under most normal conditions. Furnaces of this type may be de- 130

signed for handling very small amounts of air or quantities of air as great as 18,000 cu. ft. per minute. One standard size which is commonly employed will handle approximately 5,000 cu. ft. of air per minute, and will raise the temperature of this air from normal out-door temperature to 1000 to 1200 degrees. Such a furnace requires a consumption, when burning ordinary fuel oil, of approximately 45 gallons of oil per hour. An equivalent amount of coal will produce the same results.

In the description which has been given of refractories specific mention has been made of carborundum for the reason that this material is particularly suited for transmitting relatively large quantities of heat per unit volume and at the same time will withstand high temperatures for long periods. It is of course entirely possible to use many other materials for this purpose, such as magnesite, alundum, graphite, etc. Fused quartz may be employed as well as heat resisting alloys, such as nichrome, silicon chrome, etc.

It will be understood that this invention is not confined to any specific material but to types of materials of the class described. The materials, however, are preferably graded as described and shown, so that the more refractory material is subjected to the high temperature, the less refractory material (resistant alloys) to the lower temperatures, and cast iron and steel to the lowest temperatures. I may find it advisable to omit any one or more of the grades described and shown.

It should be understood that one object of the inclined walls shown in sections 13 and 14, is to produce a structure which will cause the gases passing through the structure to give up a maximum amount of their heat to the walls with a minimum of resistance to the flow of the gases. This result is also secured by the longitudinal ribs and other devices which have been shown and described.

Having now disclosed my invention, what I claim as new and wish to secure by Letters Patent in the United States, is as follows:

1. A furnace for heating gases, which consists of combustion chambers having walls of relatively good conducting material, flues connecting said combustion chambers to a stack, spaces between said combustion chambers and flues for the circulation of said gases to be heated, and separating walls of lower heat conductivity than said chamber walls located in said spaces between said combustion chambers.

2. In a furnace for heating gases, a combustion chamber having walls of relatively high heat conductivity, and an adjacent wall of lower thermal conductivity arranged to be

heated by radiation from said combustion chamber wall, said adjacent wall being placed to permit the circulation of gases to be heated in contact with it.

3. An air heating furnace consisting of 70 horizontal combustion chambers communicating with vertical radiating flues, air spaces between said combustion chambers and said radiating flues and auxiliary radiation receiving walls adjacent to said combustion chambers and said radiating flues.

4. In an air heating furnace, a vertically extending radiation member enclosed in a housing, air spaces around said radiation member and within said housing, and baffles so arranged as to offer the minimum retardation of air passing in one direction through said air spaces while offering considerable resistance to air traveling in the other direction through said air spaces. 85

5. In an air heating furnace, vertically extending radiation members enclosed in a housing, air spaces within said housing adjacent to said radiation member, air openings at the upper portion of said housing, and adjustable deflectors at said air opening, said deflectors arranged to permit varying amount of products of combustion to enter said air passages. 90

6. In an air heating furnace, a vertically extending radiation member, a housing surrounding said member, baffles in said housing, air spaces adjacent to said radiation member and within said housing, an opening at the upper portion of said housing 100 to permit the entrance of air, said opening being of much smaller cross section than the air passages in said housing.

7. In an air heating furnace, a radiation member composed of surfaces arranged at a 105 slight angle to the direction of travel of gases through said radiation member and a radiation receiving member adjacent to said radiation member having a lower thermal conductivity than said radiation member. 110

8. In an air heater, a combustion chamber, a radiation member communicating therewith, a housing surrounding said combustion chamber and radiation member and a radiation receiving wall of lower thermal 115 conductivity than said radiation member, the walls of said radiation member said radiation receiving walls and combustion chamber being provided with irregularities which produce eddies in the air passing through said housing. 120

9. In an air heating furnace, a combustion chamber provided with walls of high heat conductivity, and an absorbing wall of lower thermal conductivity adjacent to said combustion chamber walls, and spaced between said absorbing wall and said combustion chamber wall, and means for circulating air over the surface of said absorbing wall. 125

10. A furnace for heating gases, compris- 130

ing a combustion chamber formed from carborundum, an adjacent wall of fire brick arranged to receive heat by radiation from said combustion chamber, and a path for 5 gases to circulate between said combustion chamber and said adjacent wall.

11 In a furnace for heating gases, a car-

borundum combustion chamber and an adjacent wall of relatively low conductivity arranged to be heated by radiation from said combustion chamber, a circulation space being provided between said combustion chamber and said low heat conductivity wall.

W. A. DARRAH.
